UNITED STATES PATENT OFFICE.

FRANCIS J. STUART, OF ST. LOUIS, MISSOURI.

TRUSS-PAD.

1,142,466.

Specification of Letters Patent. Patented June 8, 1915.

Application filed February 17, 1914. Serial No. 819,257.

To all whom it may concern:

Be it known that I, FRANCIS J. STUART, a citizen of the United States, residing at St. Louis, in the State of Missouri, have invented new and useful Improvements in 5 Truss-Pads, of which the following is a specification.

My invention relates to a pad for use in 10 connection with trusses designed for the treatment of hernia, and particularly to a truss pad adapted to be held in position by means of a suitable support and which is hollow to contain a medicament, the pad being formed with an opening in its bearing 15 face through which the medicament is constantly applied to the part under treatment.

One object of the invention is to provide 20 a pad of the character described which may be manufactured from paper fiber, or hard rubber substitutes, in a satisfactory and economical manner.

The invention consists of the features of construction, combination and arrangement 25 of parts herein fully described and claimed, reference being had to the accompanying drawing in which:—

Figures 1, 2 and 3 are respectively front, 30 rear and edge views of one form of pad constructed in accordance with my invention. Fig. 4 is a longitudinal section of the same. Fig. 5 is a view similar to Fig. 4 but showing the parts of the pad separated as they appear prior to association.

A pad of the character disclosed may be 35 turned or otherwise formed from wood, and blown or molded in several ways from vulcanized rubber, but it is desirable under many conditions to produce a pad which may be economically manufactured from 40 paper fiber or hard rubber substitutes, from which the pad can not be formed in the aforesaid ways.

My invention provides a construction and 45 a method of manufacture whereby pads of the character specified may be made from fiber or any of the ordinary hard rubber substitutes in a satisfactory, reliable and comparatively inexpensive manner.

The pad 1 may be of any suitable form 50 for the purposes and comprises a body member 2 and a closure member 3. The body member 2 is herein shown as of substantially economical formation, comprising a crown portion 4 and a base portion 5, the crest or 55 apex of the portion 4 constituting the bearing face of the pad, which is provided with

an outlet 5' for the discharge of the medicament.

The portion 2 is hollow and forms a chamber 6 in which the medicament is 60 stored, and in practice the sealed or closed base portion of the pad is fastened or applied in any suitable manner to a supporting device of any preferred construction, whereby the pad is secured upon the person 65 of the wearer. As shown, the base 5 has an opening 7 of materially greater diameter than the opening 5' and which receives the closure member 3. This opening 7 may be of any suitable shape, but is preferably circular in outline, as shown, and the closure member 3 is preferably in the form of a circular disk which is threaded, cemented or otherwise secured within the opening 7 so as to lie flush with the outer surface of the 75 base 5, thus closing the chamber 6 and making the base portion 5 solid across the back of the pad to enable it to be properly applied to the supporter.

The edges of the opening 7 and disk 3 are 80 preferably rabbeted or chamfered to lap and form a close joint, whereby a tight connection and sealing action is afforded. The body member 1 and closure member 3, in the process of manufacture of the pad, are 85 separately molded from the paper fiber or hard rubber substitute and then assembled and united in the manner described. By this means I am enabled to produce a hollow body from materials of the character specified which can not be blown or molded otherwise in a satisfactory manner, the finished pad being for all purposes as strong and durable as if blown or molded in a single piece. A pad thus made provides a storage chamber or cavity 6 of some considerable size to 90 receive the charge of medicament which gradually feeds through the outlet 5' and is absorbed by the tissues, by which the parts under treatment are strengthened and relief 95 afforded or such an action induced as to restore normal conditions.

While the form of pad herein shown is preferred, it will of course be understood that the exterior configuration of the pad may be of a character adapted for the treatment of any form of hernia.

I claim:—

1. A truss pad comprising a substantially flat base plate having a flat inner face and a central projection from its outer face, said projection consisting of a hollow boss of ap-

proximately frusto-conical form, said base plate having a circular opening therethrough communicating with the cavity of the boss, and said boss being provided with an opening in the apex thereof, said boss extending throughout its area beyond the outer face of the base plate, and a flat circular disk peripherally secured within the circular opening in the base plate so as to lie wholly within said opening and having a flat outer face lying flush with the rear face of said base plate.

2. A truss pad comprising a substantially flat base plate having a flat inner face and a central projection from its outer face, said projection consisting of a hollow boss of approximately frusto-conical form, said base plate having a circular opening there-

through communicating with the cavity of the boss and formed with screw threads 20 therein, the said boss being provided with an opening in the apex thereof and extending throughout its area beyond the outer face of the base plate, and a flat circular disk having peripheral threads engaging the 25 threads of the circular opening in the base plate, whereby said disk is secured wholly within the opening, the disk being provided with a flat outer face lying flush with the rear face of said base plate. 30

In testimony whereof I affix my signature in presence of two witnesses.

FRANCIS J. STUART.
